UNITED STATES PATENT OFFICE

167,553

HAIR HOLDER

Siegfried Behr, Flushing, N. Y.

Application May 17, 1952, Serial No. 19,772

Term of patent 7 years

(Cl. D86—10)

To all whom it may concern:

Be it known that I, Siegfried Behr, a citizen of the United States, residing at Flushing, county of Queens and State of New York, have invented a new, original, and ornamental Design for Hair Holder, of which the following is a specification, reference being had to the accompanying drawing, forming part thereof.

Fig. 1 is a perspective view of a hair holder, showing my new design.

Fig. 2 is a top plan view thereof.

Fig. 3 is a front view thereof.

Fig. 4 is a side view thereof.

Fig. 5 is a rear view thereof.

I claim:

The ornamental design for a hair holder, as shown.

SIEGFRIED BEHR.
